G. H. COCHRAN, OF KANSAS CITY, MISSOURI

THRASHING ATTACHMENT FOR BINDERS

Application filed January 22, 1929. Serial No. 334,333.

The present invention relates to improvements in harvesting machines and has reference more particularly to a thrashing attachment for grain binders.

5 One of the important objects of the present invention is to provide a grain thrashing attachment comprising a unitary structure that will at all times be positive and efficient in its operation, the same being further of such construction as to facilitate its association with a binder without necessitating any material alterations of the binder.

A further object is to provide a thrashing attachment for binders wherein means is 15 provided whereby the operator of the machine can effect the operation of the separator unit that includes a rotary drum, without having to leave his seat.

A further object is to provide a thrashing attachment for grain binders that includes 20 means for tightening the strings to take up any slack that may occur therein, additional means being provided whereby the rotary drum of the separator unit may be operated by the bull wheel of the binder.

25 Other objects of the invention will become apparent as the nature of the invention proceeds and when taken in connection with the accompanying drawings.

30 In the accompanying drawings, forming a part of this application and wherein like reference characters designate like parts throughout the several views:

Figure 1 is a top plan view of a conventional grain binder showing my improved thrashing attachment associated therewith.

Figure 2 is an elevational view of the attachment looking at one side thereof.

Figure 3 is a longitudinal sectional view 40 through the attachment.

Figure 4 is a vertical section taken approximately on the line 4-4 of Figure 3.

Figure 5 is a similar section taken on the line 5-5 of the same figure.

45 Figure 6 is a detail of the clutch that is controlled by the foot pedal.

Figure 7 is a detail elevational view of the chain tightening mechanism, and

50 Figure 8 is a view similar to Figure 6, showing the hand operated clutch that is as-

sociated with the drum supporting shaft at one end thereof.

In the drawings, wherein for the purpose of illustration is shown the preferred embodiment of my invention, the numeral 1 designates generally a conventional grain binder, the grain that is cut by the cutting mechanism shown at 2, being delivered upon the conveyor 3, which conveyor carries the cut grain onto the conveyor 4. This last mentioned conveyor is disposed directly over the endless conveyor 5 of my improved attachment which conveyor is mounted within a frame 6 supported at the rear end of the attachment constituting the present invention. 55 The attachment per se is denoted generally by the reference character 7 and the same is adapted to be mounted on the side of the binder 1, in lieu of the usual stacking or binding mechanism usually associated with a 60 grain binder.

A rectangular shaped casing 8 is included as a part of the thrashing attachment, the same being supported on the frame 9 at the rear end of which frame there is arranged the 75 platform 10 and from which platform extends upwardly the seat supporting bracket 11, the seat being shown at 12 in Figure 2. A pivoted foot treadle 13 is also arranged on the platform 10, for a purpose to be presently described.

Arranged within the top portion of the rear end of the casing 8 is a separator unit that includes a cylinder 14 of sectional construction, the top section being hinged for vertical 85 swinging movement as at 15. Teeth 16 are arranged on the inner face of the sections of this cylinder and cooperating with these teeth are the teeth 17 that extend radially from the drum 18 arranged for rotation within the cylinder and this drum is secured on a shaft 19 that extends centrally through the respective ends of the cylinder. The means for driving the shaft and the drum secured thereon will be described in detail later.

90 The cylinder 14 is formed at one side with an inlet 20 with which cooperates the discharge end of the endless conveyor 5 for receiving the material to be separated. The bottom of the cylinder 14 is open to permit the 95 100

disintegrated material to be discharged onto an inclined deflector plate 21, that has co-operation with the upper endless conveyor 22 and the screen 23 associated therewith. The 5 end of the casing 8 remote from the rotary drum and its cylinder is formed with an outlet opening 24, whereby the endless conveyor 22 will carry off the straw while the grain will fall through the screen 23 onto the underlying 10 unit 25, that includes an endless conveyor 26 and the imperforate plate 27 over which the upper flight of the endless conveyor 26 travels and the grain falling on the plate 27 is carried toward the discharge mouth 28 that has 15 communication with the grain receiving compartment 29 and air is forced through the grain in the compartment 29 through the medium of the blower fan 30 and the conduit 31 as shown very clearly in Figure 3. In this 20 manner, all chaff will be blown out of the grain through the mouth 28 outwardly of the casing 8. A discharge neck 32 extends from the bottom of the compartment 29 and a sack or the like is placed around this neck for 25 receiving the grain.

Access to the endless units arranged within the forward portion of the casing 8 is had through an opening provided therefor in the top of the forward end portion of said casing, 30 a hinged door 33 normally closing this opening.

The blower fan 30 is mounted within a suitable casing 34, and one end of the shaft upon which the blower fan is mounted extends 35 through the adjacent end of the casing and carries a sprocket wheel thereon for driving the rotary fan. In addition this side of the casing is provided with air inlet openings 35, a sliding closure 36 being provided for disposition over these air openings, as also 40 clearly indicated in Figure 2.

A sprocket wheel 37 is secured on one end of the drum supporting shaft 19 and the smaller sprocket wheels 38 are arranged on the adjacent side of the casing in alignment with the sprocket wheel 37 and the sprocket wheel 39 secured on the outer end of the blower fan supporting shaft, and trained over these aligned sprocket wheels is the sprocket 45 chain 40. Means is provided for taking up the slack in this chain 40 and to this end I provide the pivoted lever 41 that carries a sprocket wheel 42 adjacent its pivoted end and this sprocket wheel engages with the sprocket chain 40 as clearly indicated in the drawings. In addition, means is provided for maintaining the pivoted lever in any adjusted 50 position and this adjusting means is shown broadly at 43, in Figure 2.

60 Additional aligned sprocket wheels are arranged on the shaft 19 and the adjacent end of the shaft that carries the roller nearest to the separator cylinder and over which is trained the endless conveyor belt 5, a 65 sprocket chain 44 being arranged over the

last mentioned pair of sprocket wheels whereby the endless conveyor 5 is actuated simultaneously with the operation of the rotary drum 18.

A remotely operated clutch mechanism shown generally at 45 is associated with the aforementioned end of the shaft 19 and the pivoted bell crank lever 46 that actuates this clutch is operated by a cable 47 and is attached to the pivoted treadle 13.

The shaft 19 is driven from the bull wheel 48 of the grain binder by means of the sprocket chain 49 and a manually operable clutch mechanism shown generally at 50 in Figure 8 is associated with this end of the shaft 19 for throwing the same into or out of cooperative engagement with the bull wheel of the binder. The hand lever for actuating this clutch mechanism is shown at 51, also in Figure 8.

For the purpose of taking up the slack in the sprocket chain 29, there is provided the slack adjuster shown at 52 in Figure 7, and the same includes the pivoted lever 53 carrying an arm 54 on the outer end of which is arranged the sprocket wheel 55 that engages with the sprocket chain 48. It is of course understood that the bull wheel is arranged on the shaft 56 and that a sprocket wheel is secured on this shaft for cooperation with the sprocket chain 48.

The endless conveyor 4 is adapted to be driven by operatively connecting the same with the driving mechanism provided for the endless conveyor 3 and this arrangement is clearly shown in Figure 1.

If desired, a small electric motor may be arranged on the platform 10 for independently actuating the movable parts of the thrashing attachment. It might also be well to mention at this point that the sprocket chain 40 cooperates with suitable sprocket wheels 56, and 57, arranged on the outer ends of the shaft of the upper and lower grain separating units arranged in the casing 8 for effecting the actuation of the endless conveyors of these units.

A thrashing attachment of the above mentioned character can be readily and easily installed after the binding mechanism has been removed from the binder and the attachment will at all times be positive and efficient in carrying out the purposes for which it is designed.

Furthermore the clutch mechanism will act as a safety device for the rotary drum and the cylinders within which the drum operates so that this part of the machine will not be broken or become clogged up.

While I have shown the preferred embodiment of my invention, it is to be understood that various changes in the size, shape and arrangement of parts may be resorted to, without departing from the spirit of the in-

vention or the scope of the appended claim.

I claim:

In a thrashing attachment for binders, a unitary structure comprising a supporting frame, a casing mounted on the frame, a cylinder open at its bottom arranged on the top of the casing, teeth arranged on the inner side of the cylinder, a toothed drum mounted for rotation in the cylinder, said cylinder being formed in the side with an inlet, a conveyor arranged on the casing for receiving the grain from said binder and delivering the same to the inlet in the cylinder, separating units arranged within the casing adapted to receive the material discharged through the bottom of the cylinder, a grain receiving compartment arranged below said separator units, a blower fan having communication with the compartment, a trash outlet for association with the separating units and the grain compartment, means for operating all of the movable parts, said separating units including upper and lower spaced plates, the upper plate being perforated, and endless conveyors arranged around said plates, said casing being provided with a tapered discharge mouth adjacent one end of the lowermost separator unit, the upper wall of said discharge mouth constituting a discharge chute for the upper separator unit, said upper separating unit extending forwardly beyond the lower separating unit.

In testimony whereof I affix my signature.

35 FILO J. DECKER.
